UNITED STATES PATENT OFFICE.

CHARLES D. MEYER, OF SEATTLE, WASHINGTON.

RIFLE.

Application filed September 29, 1923. Serial No. 665,669.

To all whom it may concern:

Be it known that I, CHARLES D. MEYER, a citizen of the United States, residing at Seattle, in the county of King and State of Washington, have invented certain new and useful Improvements in Rifles, of which the following is a specification.

This invention relates to breech block mechanism for repeating rifles and its object, generally, is the improvement in devices of this character to render the same more rapid, safe, convenient and efficient in operation.

More specific objects and advantages of the invention will appear in the following specification.

The breech action of the present invention is of the rectilineal type or so-called "straight pull", like the Canadian Ross, the Swiss army rifle, 1889/96, and the Austrian; but having none of their inherent faults or defects and is designed as an improvement to the standard bolt action type, known as the Mauser, Manlicher, U. S. Springfield, Model 1903, and others, their most advantageous characteristics being retained.

In the following description the standard bolt action will be referred to as "turn up" type and the rectilineal as "straight pull", the name Mauser, Manlicher, U. S. Springfield, designating similar turn up types, because to open the same the handle is turned up, whereas in the rectilineal type, the pull is straight back.

Hitherto, straight pull actions have been unsatisfactory chiefly because they lack the power to insert and extract cartridges, mainly the extracting, as the cartridges oftentimes stick in the chamber after being fired, as with their principle, the riflemen cannot exert the power than can be obtained in the regular pull-up-and-cam-action.

As an example, the Ross straight pull has practically no extracting power, has no safety lugs and, should the locking lugs give way under pressure, the bolt will fly back and severely injure the rifleman. Also, if due to a pierce-primer, gases will enter the bolt by the firing-pin hole and thereby lead to the rear of the same to act on the bolt as a piston and the operating slide as its cylinder to push them apart and thus unlock the action which oftentimes causes disaster.

The Swiss army rifle, also a straight pull, like the Ross has several disadvantages. Its power of extraction is better, however, as

will be explained later; but, like the Ross, has no safety lugs and acts the same under excess pressure; its receiver is complicated and difficult to manufacture. Its locking lugs being located at a distance from the rear of the chamber, is considered as objectionable by expert riflemen and proves a detriment to accuracy in shooting due to the excessive spring to which the action is subject at the instant of firing causing a stretch of the metal between the chamber and the locking lugs recess in the receiver, the amount of such stretch or spring being in proportion to this length. Cartridges fired in a rifle having its locking mechanism away from the chamber invariably expand and cannot be reinserted in the chamber.

Rigidity of locking mechanism is what is required in rifles, and it is found only in the locking system of the regular turn-up action of the Mauser, Manlicher, or similar type.

But these last actions are slower, and for the average rifleman are hard to manipulate rapidly requiring four motions,—first, a turn up movement; second, a pull back movement; third, a push forward movement; and fourth, a turn down movement.

The first above mentioned movement is the one requiring the most power to effect and is the one in which the rifleman is able to exert the least, due to the position he has to assume when firing, the location of the bolt handle, and the direction in which he has to apply the force. He can therefore use but a fraction of his muscular effort to lift the handle or turn it up.

The first movement requires more power because in turning up the handle to unlock the bolt, it also cocks the piece which requires an appreciable amount of force and it also extracts the fired shell by bringing into action the cam on the bolt against the inclined surface of the receiver and thus forces the bolt backward, pulling on the cartridge, which is hooked by the extractor.

The other three movements are comparatively easy.

The advantages of the turn-up type reside in the provision of a more rigid, simple and safe construction which is adapted to modern high power ammunition, as is exemplified by the fact that they have been adopted as standard equipment by the armies of practically all nations. The principal disadvantage resides in their being slow and inconvenient to manipulate.

In my improved straight pull action I retain the regular bolt and in the accompanying drawings have shown the action with the Springfield bolt type, which is selected because it embodies features which make it particularly serviceable for assembling the action which will be discussed hereinafter.

My invention is illustrated in the accompanying drawings, in which,—

- 10 Figure 1 is a right hand elevational view of a portion of a rifle to which my improved devices are applied. Fig. 2 is a plan view of the same, and Fig. 3 is a left hand elevational view thereof. Fig. 4 is a longitudinal vertical sectional view of parts shown in Figs. 1, 2 and 3, with the bolt and parts associated therewith illustrated in retracted positions. Fig. 5 is a horizontal plan view with the parts arranged as shown in Figs. 1, 2 and 3. Fig. 6 is a fragmentary plan view of Fig. 4, the operating slide being shown principally in horizontal section. Fig. 7 is a rear elevational view of Fig. 1, illustrating the use of a cartridge shell as 25 one of the elements of the slide handle. Fig. 8 is a fragmentary plan view of the breech bolt. Fig. 9 is a similar view of the operating slide. Fig. 10 is a plan view of portions of the firing pin rod, bolt sleeve, cocking piece, 30 etc. Fig. 11 is a side elevation of Fig. 10 with the bolt sleeve shown in longitudinal section. Fig. 12 is a view in longitudinal elevation of the forward end of the firing pin and striker, the sleeve for the firing pin 35 being shown in longitudinal section. Fig. 13 is a detail sectional view taken through 13—13 of Fig. 9. Fig. 14 is a rear end view of Fig. 9. Fig. 15 is a sectional view of the receiver taken on line 15—15 of Fig. 5. Fig. 16 is a detail sectional view taken on line 16—16 of Fig. 4, and including the bolt head which is not shown in Fig. 4. Fig. 16^a is a development view of the inner peripheral surface of the receiver shown in 40 Fig. 15 and also the outer peripheral surface of the rear portion of the bolt, to illustrate the grooves thereof with respect to the operating slide shown somewhat diagrammatic, and the cocking piece. Figs. 17, 45 18, 19 and 20 are views similar to Fig. 16 with the bolt head represented in its progressive positions. Figs. 17^a, 18^a, 19^a, and 20^a, are views similar to Fig. 16^a, with the parts thereof shown in the positions which they 50 occupy when the bolt head is located as represented in Figs. 17, 18, 19 and 20, respectively. Fig. 21 is a plan view similar to Fig. 2, except that the operating slide guide is disposed at the left hand side of the rifle; 55 and Fig. 22 is a left hand elevational view of Fig. 21. Fig. 23 is a rear elevation of Figs. 21 and 22, including a cartridge for use as a handle element of operating slide, the bolt sleeve and cocking piece turned to 60 safe position.

It will be seen in said drawings that there is no change in the bolt 5 with respect to the locking lugs, safety lug, extractor and collar, from those found in the Springfield, but the handle has been omitted and a cylindrical extension indicated by 6 is added at the rear part of the bolt.

The extension 6 above referred to is of relatively large diameter and its forward end is formed to provide an extracting cam face 7, the pitch of which and its location on the bolt being the same as in the present Springfield rifle although its face is somewhat longer to extend in front of a stop 8 for one of the operating slide lugs 9 to limit the forward travel of the operating slide which is indicated generally by 10.

On the periphery of the said extension there is provided at diametrically opposite sides two grooves 11 and 12, each having an angle of one quarter of a turn for its length, in said extension. These grooves are of suitable widths and depths to allow the operating slide lugs 9 to move or slide in them freely.

As best shown in Figs. 16^a to 20^a, the left sides of the 9¹ of these grooves, starting forward, are parallel to the axis of the bolt for a short distance and are then extended helically to the right in such a manner as to terminate on the next quarter into a hook shape stop as at 9² to limit the operating slide lugs in the rearward travel of the slide.

The right sides 9³ of the respective grooves, beginning forward, also start parallel to the axis of the bolt but for only half the distance of the left sides and thence helically to the right at the same or greater angle than the opposing angular portions of said left sides for about half the length of the latter where they make an abrupt turn to the right as at 9⁴ thus making an angle of approximately 90° with the axis of the bolt. The right sides then continue for a length not less than one and one-half times the width of the operating lugs 9 and thence, as at 9⁵, parallel to the axis of the bolt. 13 represents an angular recess provided in the rear end of extension 6 to receive the nose 14 of the cocking piece 15.

The recess 13 has one of its sides, as 16, parallel with the bolt axis and its other side 16¹ arranged substantially as shown in Figs. 4 and 16^a to 20^a inclusive.

The recess 13 extends to the bolt sleeve 17 socket and its length is such as to limit the forward travel of the firing pin assembly, shown in Figs. 11 and 12, the nose 14 of the cocking piece thereupon engaging against the end of said recess.

The interior of the bolt extension 6 is bored and threaded to provide a socket for the bolt sleeve 17 and firing pin assembly.

The receiver.—Interior details of the receiver 18 forward of dotted line 15—15,

Figs. 4 and 5, are similar to the Springfield, but to the rear of such line the receiver is extended as at 18¹ to cover the bolt mechanism and also provide a suitable base 19,

5 Figs. 1 and 2, for a rear sight (not shown) as far back as possible and in a position almost unattainable on rifles with a turnup action. With my type of receiver almost any sight can be installed, for instance a 10 telescope sight can be attached as low as desired as there is no bolt handle to clear, or a peep or aperture rear sight can be used advantageously. As a rifle is no better than its sight, this feature of my invention is sure 15 to appeal to riflemen.

According to the present invention, the receiver is formed or constructed to provide bearings 20 and 21 for the operating slide guide 22 which may be installed on either the left side as in Figs. 21, 22, 23, or 20 on the right side of the receiver, as in Figs. 1, 2, 4, 5, and 7; however, the right hand arrangement is preferred because the bolt stop, magazine cut off and ejector are retained as hitherto in the Springfield. The 25 gas escape vent 23, Fig. 5, is located on the left with the operating slide guide on the right side and is located on the right when the guide is on the left as at 23¹ in Fig. 21.

30 *Operating slide.*—The function of the operating slide 10 is to rotate the bolt one-fourth of a turn to unlock it and at the same time withdraw the firing pin and hold it back. The operating slide then serves to 35 draw the bolt to the rear, then push it forward again, and finally turn the bolt a quarter of a turn to lock it, having meanwhile hooked the firing pin to the sear, all the above being performed in two motions 40 of the operating slide.

The main body 24 of said slide is of a cup shape, interiorly of the mouth of which is located at diametrically opposite sides, the two operating lugs 9 which are adapted 45 to slide in the bolt grooves 11 and 12. The rear end of said body is provided with a central aperture 25, see Fig. 14, for the bolt sleeve 17 and permits the latter to slide and rotate freely therein. Above the aperture 50 25 is a communicating slot 26 to permit the passage of the stop-block 27. At the bottom of the aperture 25 and diametrically opposite the slot 26, is a second slot 27¹ which serves as a way for the cocking piece nose 55 14, the length of said way being such as to have the inner end thereof serve as a stop with respect to said nose thereby limiting the forward travel of the firing pin.

60 Protruding from the rear of the body 24 is a block 28 having an inclined outer surface 28¹ the pitch of which is the same as the pitch of the screw thread 29 of the bolt sleeve and its projection from the body is slightly greater than the said pitch.

65 At one side of the body element 24, the

slide is provided with the tubular guide 22 which is mounted for reciprocating movements in the bearings 20 and 21 above mentioned.

The guide 22 is of a length about equal 70 to the length of said receiver, the end 22¹ of the guide is tapered, as shown in Fig. 5, said end being divided by longitudinal slots such as 30 into a plurality of segments which at their extremities are formed with 75 inner peripheral flanges or beads 31 to afford resilient claws which are adapted to snap over the shoulder of a stud 32 to releasably hold the operating slide in its closed position. 80

The above described locking devices serve to positively hold the operating slide when the action is fully closed and prevent any partial opening movement of the bolt as oftentimes occur with turn-up actions and 85 is a frequent cause of misfire.

The stud 32 is of a general pear shape and cooperates with the claw end of the slide guide in a manner somewhat similar to a glove snap fastener. The stud, as shown, is 90 provided with a screw threaded shank or plug element 32¹ which fits in a screw thread provided in the receiver part 20.

The slide is also provided with a handle 95 33 projecting laterally therefrom for reciprocating the slide, and as illustrated said handle is provided with an eye 34 which is machined to hold a cartridge 35, Fig. 23, or a cartridge shell as 35¹ in Fig. 7, of the type intended for use in the rifle to which 100 the present invention is applied.

The bolt sleeve 17 included in my invention serves to receive the back thrust of the main spring 36, at the same time permitting 105 the bolt to rotate independently of any of the members which are attached thereto and to lock the complete action when desired.

Said sleeve is bored and slotted to accommodate the firing pin rod 15¹ and said 110 cocking piece assembly to enable the same to slide longitudinally therein. The forward part of said sleeve is threaded as denoted by 29 (Figs. 10 and 11) so that it can be screwed into the rear end of the bolt as 115 indicated by dotted lines in Fig. 4.

Provided on said sleeve is the stop block 27 having a front face 27² disposed at an angle corresponding to the pitch of the screw thread 29 of the bolt sleeve and also 120 with respect to the pitch of the surface 28¹ of the slide projection 28. The distance of the stop block 27 from the screw thread 29 is such that when the bolt and operating 125 slide are assembled within the receiver and fully closed, the said sleeve may be screwed into the bolt until the stop block 27 revolvably engages the block or projection 28 at the back of the slide.

The stop block is desirably provided with 130

an assembling catch 37 and a spring 38 which tends to retain the catch in disengaged position. When the firing pin is pulled back and the catch pressed down by the operator, said catch serves to hold the firing pin assembly on the bolt sleeve 17 while screwing the latter into or unscrewing it from the bolt, said catch, however, is a convenience and not a necessity. The assembling catch is coupled with the bolt sleeve as by means of a pin 39.

The cocking piece 15 of my invention is cocked by a straight pull backward and not by the rotation of the bolt, thus greatly eliminating friction.

The sear 40 and the trigger 41 are substantially similar to known construction, although the lengths and shapes of same are modified to suit the organization hereinabove described. The cut-off spindle 42 for my improved mechanism is made longer to suit the receiver.

To assemble and dismount the action.—The operator in one hand holds the bolt 5 horizontally by its forward portion, the rear end toward him, and with the safety lug 43 up, and directed slightly toward the left as represented in Fig. 8. With his other hand he holds the operating slide 10 with its handle 33 on the right side (see Fig. 9) back of the bolt when in its Fig. 8 position, the operating lugs 9 then being in positions to register with the bolt grooves 11 and 12, whereupon the bolt is inserted in the slide 35 as far as it will go without turning. The bolt is now turned until its safety lug 43 is vertical, that is a right angle to a plane passing through the center of the slide and guide. Thus the bolt and slide are inserted in the receiver, having previously turned the cut-off 44 to clear locking lugs races 45, Fig. 15, then push the handle fully home, turn down the cut-off thumb piece 44¹, Figs. 2 and 3, permitting the operating slide and bolt to be worked back and forth.

With the bolt and slide assembly in the receiver and fully home, insert the cocking piece 15 and firing rod 15¹ assembly, into the bolt sleeve 17, then place on the rod the main spring 36, compress it, now slip over the rod the firing pin sleeve 46, then hook on the striker 47 and then let go the sleeve which slips over the rear portion of the striker to secure the same to said rod.

Now hold the bolt sleeve in one hand and at the same time press on the assembling catch 37; with the other hand pull on the cocking piece 15 until it is felt that the assembling catch 37 has dropped into the forward part of the cocking piece, see Fig. 11, to hold the firing pin assembly back on the sleeve.

When thus arranged insert the firing pin and bolt sleeve assemblies through the rear 65 of the bolt and screw the same as far as it

will go, that is until the stop block 27 on the bolt sleeve strikes the block 28 on the back of the operating slide.

Now pull on the cocking piece to effect the release of the assembling catch, and gently release your hold or pull until the cocking piece nose bears against the sear. The action is now fully assembled and ready to fire.

To dismount proceed in the reversed order 75 doing the last explained operation first and the first, last.

From the foregoing explanation, it will be seen that no tools are required to assemble or dismount my improved rifle action.

The operation of my invention may be described as follows, and with reference, more particularly, to Figs. 15 to 20 and 16^a to 20^a, inclusive:

Assuming the action is assembled, closed 85 and the trigger pulled the action will then be as represented in Figs. 16 and 16^a. The operator by means of handle 33 then pulls the operating slide (Fig. 9) rearwardly to cause the same to travel progressively 90 through the position in which it is represented in Figs. 17 and 17^a into its position in which it is represented in Figs. 18 and 18^a and in Figs. 19 and 19^a. In its forward or first position (Fig. 16^a) an operating lug 9, for clearness only one of which is shown in said diagrammatic views, is seated against the forward end of slot 11; the cocking piece 14 is at the forward end of the recess 13 and also against the forward 100 end of the slot 27¹, indicated diagrammatically Figs. 17^a and 18^a of said operating slide; the locking lugs 50 and the safety lug 43 being in their closed positions; and the cam face 7 of the bolt extension 6 being out of contact with the inclined surface 51 of the receiver 18.

In pulling the operating slide into its Fig. 17^a position, the same is moved a distance indicated by letter A in Fig. 17^a resulting in the operating lug 9 acting against side 9¹ of groove 11 thereby causing the bolt to rotate a distance circumferentially as indicated by B, the locking lugs 50 and the safety lug 43 being correspondingly 115 revolved; the cocking piece 14 is brought by the operating slide into its cocked position; and the cam face 7 of the bolt is brought into contact with the inclined surface 51 of the receiver. In the further rearward movement of the slide from its Fig. 17^a position into its Fig. 18^a position, said slide travels a distance indicated by A² in Fig. 18^a which effects the action by causing the operating lug 9 to reach its normal rear-most position thereby completing a one-fourth rotation of the bolt, as indicated by B² thus revolving the locking lugs 50 and safety lug 43 into positions to register with the respective races 45, the cam face 7 of the 120 receiver 18.

bolt meanwhile acting against the inclined surface 51 of the receiver causes the bolt to be pushed rearwardly indicated by C to accomplish what is conventionally known as 5 "primary extraction".

The bolt now is unlocked and free, the operating slide is acting against the firing pin which is held on the bolt by the bolt sleeve 17 through the medium of the main 10 spring 36 so, without pulling the handle further back, said spring will cause the bolt to overtake the operating slide an amount equal to D Fig. 19^a or until the operating lugs 9 engage the sides 9⁴ of the respective 15 bolt grooves 11 and 12 and the slide and bolt will be held together by the power of the main spring which tends to pull the bolt back and push the operating slide ahead thus keeping them in contact, the bolt lugs 50 being in their respective races (see Figs. 19 and 19^a) cannot turn either way and the bolt is locked against rotation.

By pulling on the handle the bolt is 20 dragged back, its lugs sliding in the races therefor until one of locking lugs comes into contact with the cut off 44, Fig. 5, whereby the bolt will be checked or stopped, the operating slide will also be stopped, but less sharply as it is held by the main spring it 25 may be felt if the handle is further pulled rearwardly, thus somewhat releasing the shock on the cut-off and on the bolt locking lug referred to, incidentally giving the operator's hand a rebound for closing the action when it is desired to work the same rapidly.

However, the yield of the main spring is 30 limited by the operating lugs coming in contact with the hooks 9² at the ends of the sides 9¹ of the respective bolt grooves 11 and 12 thereby preventing any further backward movement of the operating slide and preventing injury to the main spring, and 35 should the handle be released it will return to the position in which it is represented in Fig. 19^a and Fig. 4.

Pushing the handle ahead will move the bolt forward to insert a cartridge in the rifle 40 chamber, the operating lugs acting on grooves sides 9⁴ will have a tendency to rotate the bolt proportional to the angles of the sides 9⁴ with respect to a plane at right angles to the axis of the bolt.

When the bolt in its forward movement 45 has traveled to within a distance equal to C, Fig. 18^a, of the end of its total travel, the cam face 7 of the bolt will engage the inclined surface 51 of the receiver and turn the bolt, the locking lugs 50, and the safety lug 43 which are then in line to register with the recesses 52 and 53, respectively, of the receiver.

As the bolt begins to turn the main spring 50 which is still pulling on the slide facilitates such turning action, that is to say—the cam

acts against the inclined surface of the receiver, and the operating lugs act against the small angle sides 9⁴ of the grooves 11 and 12, the push on the handle by the operator is thus assisted by the pull of the main 55 spring—all acting together, make this motion positive and continuous until the nose of the cocking piece 14 is arrested by the sear 40 which is shown in Figs. 4 and 20^a.

The bolt has meanwhile turned sufficiently 60 to be partly locked, and the operating lugs are brought against the sides 9³ of the bolt grooves 11 and 12 (Figs. 17^a and 17) a further push forward on the handle will cause said lugs to complete the rotary movement of the bolt, see Figs. 20^a and 20, and lock it against rotation as it will be seen that the operating lugs 9 are now at the ends of said grooves which are parallel with the axis of the bolt to accordingly prevent the 65 bolt being turned in either rotary direction.

The operating slide, being at the end of its forward travel, has become locked by being engaged by stud 32. The rifle is now 70 loaded and ready to fire. If the operating slide was not pushed to the limit of its travel or if it was purposely placed at any position between those in which it occupies in Figs. 17^a and 16^a the bolt would be partly 75 closed, should the trigger then be pulled the firing pin will be prevented from reaching the cartridge primer because the nose 14 of the cocking piece will strike the end of the slot, indicated by 27¹ in Figs. 17^a and 4, in the underside of the operating slide thereby 80 causing the slide to be urged ahead to close the bolt and causing a misfire.

The inclined side 13¹ of the recess 13 at the rear of the bolt, into which the cocking piece nose slides when the trigger is pulled, 85 does not at any time touch the said nose except at the end of said recess.

To put the action at safe, the rifle being 90 cocked, pull on the cocking piece 15 until its nose 14 is withdrawn from the operating slide slot 27¹ and then turn it to the left a quarter of a turn. This simple movement 95 will also serve to lock the action as the stop block 27 on the bolt sleeve 17 which is now out of register with its opening 26 and to the rear of the operating slide preventing 100 said slide being pulled to the rear, see Figs. 23 and 7.

This safety is simple, requires no parts 105 additional to those herein shown and described, is durable, easily operated, and can be manipulated readily with gloves or mitts.

With regard to the extracting power of 110 my improved action, it will be apparent from an inspection of 16^a that when the action is closed the extracting cam 7 on the bolt is at a certain distance from the inclined surface 51 on the receiver and that the handle 33 has to travel to the rear a distance 115 equal to A in 17^a before said cam comes in 120

contact with said surface and in doing so the operating slide will acquire momentum due to the speed of its travel and the cam will encounter the inclined surface 51 with 5 a striking force having greater energy than is obtainable by a direct pull.

It is also to be noted in the present invention side surfaces of the grooves 11 and 12 against which the operating lugs 9 act 10 on the bolt to cause it to rotate, are at approximately the same radial distance from the bolt axis as the extracting cam 7 thus transmitting an extracting power in the ratio of 1 to 1, see Figs. 4 and 6.

15 In the straight pull action, Ross, Swiss, etc., hereinbefore described, the power is transmitted in a ratio of less than one to one due to the locations where the force is applied being closer to the axis of the respective bolt than the locking lugs thereof, which also function as extracting cam. Also in said straight pull actions the extracting motion commences when the bolt begins to rotate and thus, having no play, simply 20 transfers one straight motion into another straight motion which is subject to the ratio of less than one to one as explained above.

In the straight pulls, heretofore, when a shell is stuck so is the bolt, its operating 25 handle cannot readily be started because the handle and the extracting lugs must start simultaneously, the rifleman cannot therefore exert sufficient pull to dislodge the shell. A shell does not need to be very tight in a 30 chamber to withstand the strongest effort by the rifleman to pull it out with such straight pull action.

To illustrate the principle of the extracting action of my invention, assume that a 35 nail is driven into wood say half an inch, and it is desired to withdraw or extract it by hand, it will require a stronger pull, perhaps more than one can exert; however, a light hammer tap under the nail head will 40 enable it to be easily extracted. Now suppose a shell sticks in the chamber of a rifle fitted with my improved action, the rifleman pulls the handle slowly to the rear and discovers that the shell is stuck. With this action 45 he is able to work the operating slide a distance to the rear sufficient to cock the piece, see Fig. 17^a thus eliminating the thrust of the main spring on the operating slide. Now again closing the action for a 50 new start and having no main spring power to contend with, working the handle rapidly the cam will strike the inclined surface of the receiver with considerable force and be capable of dislodging the tight shell. With 55 the type of handle provided for this rifle action and the direction of the applied forces to work it, the rifleman is able to advantageously use his muscular efforts under ordinary shooting conditions, that is—without 60 removing the rifle from the shoulder—than

he would be able to do with a rifle equipped with the standard turn-up bolt. With the turn-up bolt type the turning up action tends to impart a rotary movement to the rifle with respect to its longitudinal axis 70 which movement must be resisted by the rifleman's left hand, which grips the rifle stock so that when a shell is stuck in the chamber the bolt handle is lifted or turned to bring the extracting cam against the inclined surface on the receiver. 75

In other words, the bolt handle of the turn-up bolt providing a greater leverage than the hold of his left hand on the rounded stock, the rifleman is oftentimes compelled to change his position to secure supplemental resistance on the reaction side such, for instance, as placing the toe of the stock on the ground or holding the stock between his body and right arm, between his 80 legs, etc.

With the straight pull, moreover, the reaction is in the direction of the axis of the rifle or against the shoulder with the tendency to keep it there. 90

What I claim is:—

1. In a rifle action, an operating slide provided with lug elements, and a bolt of the Mauser type with its rear portion formed to serve as an extracting cam and also as a stop for the lugs of the operating slide. 95

2. In a rifle action, a bolt sleeve, and an operating slide having an opening in the end thereof through which said bolt sleeve operates, said bolt sleeve being provided with a stop block and the operating slide is provided with a slot for the passage of said stop block. 100

3. In a rifle action of the rectilinear type, a breech bolt, a bolt sleeve provided with a stop block thereon, a cocking piece, and an operating slide having in its rear end an opening for said bolt sleeve, a slot for said stop block and a way for the cocking piece. 105

4. In a rifle action a breech bolt, a bolt sleeve provided with a stop block thereon, a cocking piece, an operating slide having in its rear end an opening for said bolt sleeve, a slot for said stop block and a way for the cocking piece, and a block provided on said operating slide to be engageable by the stop block of the bolt sleeve to limit the rotary motion of said bolt sleeve. 115

5. In a rifle action, an operating slide having at one side thereof a guide to afford rectilinear movements to said operating slide, said guide is engaged by devices provided on the receiver to lock the operating slide thereto in its closed position. 120

6. In a rifle action an operating slide having at one side thereof a guide to afford rectilinear movements to said operating slide, and wherein the end of the guide is engaged by devices provided on the receiver for lock- 125 130

- ing the operating slide thereto when the operating slide is in its closed position.
7. In a rifle action, an operating slide provided with a handle having an aperture 5 to receive a cartridge shell.
8. In a rifle action, a bolt sleeve including a stop block serving to lock the operating slide to the breech bolt when in their closed positions.
10. 9. In a rifle action, a bolt, a bolt sleeve containing means to hold the firing pin assembly in its rearmost position with respect to said bolt sleeve.
10. In a rifle action, a bolt sleeve, a stop 15 block thereon, a firing pin assembly, and means rendered operative by turning the bolt sleeve and firing pin assembly to lock the action in safe position.
11. In a rifle action of the rectilinear 20 type, an operating slide having a guide element, and a receiver provided with spaced apart bearings in which is slidably mounted the guide element of the operating slide, the space between said bearings serving as a 25 passageway for extracted shells.
12. In a rifle action having an operating slide and a receiver provided with bearings for the guide element of the operating slide, wherein interengaging parts are provided on 30 the receiver and the guide element of the operating slide for securing the latter in its closed position.
13. In a rifle action of the rectilinear type, a receiver provided with an inclined surface, 35 a breech bolt having an extracting cam, and means for imparting rotary motion to said bolt whereby the cam thereof engages the inclined surface of the receiver to effect the extracting of a shell.
40. 14. In a rifle action of the rectilinear type, a receiver having an inclined surface therein, a breech bolt having a cam thereon, said breech bolt being provided with operating 45 grooves, a bolt sleeve and firing pin assembly, and an operating slide provided with lugs engaging in said operating grooves, arranged and cooperating so that the main 50 spring of said assembly will effect a primary rotation of said breech bolt in the closing operation of the same.
15. In a breech action rifle, the combination of a receiver having races, a bolt having locking lugs adapted to engage within said 55 races, a longitudinally movable operating slide slidingly associated with said bolt, and connections comprising operating lugs and grooves between said slide and the bolt by which the latter may be rotated by reciprocating the former, each of said grooves having the rear portion of one of its sides formed to provide a stop and the other side of the groove formed to provide a shoulder, 60 said stop and shoulder being arranged in spaced apart relation longitudinally of the bolt axis and in opposed relation with each other whereby the operating lugs are movable between the respective stops and shoulders without imparting any motion to said bolt.
16. In a breech action rifle, the combination of a receiver having races, a bolt having locking lugs adapted to engage within said races, a longitudinally movable operating slide slidingly associated with said bolt, and connections comprising operating lugs and 70 grooves between said bolt and slide by which the latter may be rotated and reciprocated by the former, said grooves each having at one side thereof a stop and in opposed relation thereto at the opposite side of the 75 groove a shoulder between the respective stops and shoulders said operating lugs are adapted to reciprocate without imparting any rotary or rectilinear motion to the bolt.
17. In a breech action rifle, the combination of a receiver having races, a bolt having locking lugs adapted to engage with said races, a longitudinally movable operating slide slidingly associated with said bolt, and connections comprising operating lug and 80 groove connection between said bolt and the slide by which the latter may be rotated and reciprocated by the former, said grooves being arranged to afford lost motion to the operating lugs whereby said connection will 85 allow said bolt and slide a relative longitudinal movement with respect to one another when said bolt is unlocked thus preventing said slide to communicate to said bolt any rotary motion until the bolt is returned to its locking position.
18. In a breech action rifle, the combination of a receiver having races, a bolt having locking lugs adapted to engage within said 90 races, a longitudinally movable operating slide slidingly associated with said bolt, and connections comprising operating lugs and 95 grooves connection between said bolt and the slide by which the latter may be rotated and reciprocated by the former, said grooves having at the opposite sides of each a stop and a shoulder respectively which stop and shoulder are spaced apart longitudinally of the bolt to a distance greater than the length of the respective operating lug longitudinally of the slide to allow said bolt and slide a relative longitudinal movement with respect to one another when said bolt is unlocked thus allowing said slide to impart to 100 said bolt a rectilinear motion only while the locking lugs engage within said races.
19. In a rifle action, the combination of a receiver having locking-lug-recesses and lug-races therein, a breech bolt having locking lugs and provided with helical grooves, an operating slide having lugs adapted to engage said grooves to rotate and reciprocate the bolt, said grooves being so arranged that when the breech bolt is fully unlocked by the operating slide said slide is rendered 105 110 115 120 125 130

incapable to rotate said breech bolt by a longitudinal movement of said bolt with respect to said slide until the breech bolt is returned to its locking position.

5. 20. In a rifle action, the combination with a receiver, an operating slide and a breech bolt assembly comprising a breech bolt, a firing pin, a main spring surrounding said pin, a cocking piece, and a bolt sleeve adapted to be screwed into the breech bolt, of means whereby said breech bolt assembly and the operating slide are automatically telescoped together at the instant said breech bolt is unlocked thus releasing said breech bolt from rotary motion from said slide and allowing them to reciprocate freely together.

21. In a rifle action, the combination with a receiver, an operating slide and breech bolt assembly comprising a breech bolt, an extractor mounted thereon, a firing pin, a main spring surrounding said pin, a cocking piece, and a bolt sleeve adapted to be screwed into the breech bolt, of means to eliminate rotary movement of said breech bolt at the instant said breech bolt is unlocked, said means being effected by the main spring which causes the breech bolt to retrograde a distance upon said operating lugs within the slide.

30. 22. In a rifle action, a receiver having locking lug races, a breech bolt having locking lugs and a safety lug and helical grooves, an extractor mounted upon said breech bolt, an operating slide capable of turning the breech bolt into locked and unlocked positions and move said bolt and the extractor along said receiver races when reciprocated, means provided in said grooves to longitudinally engage said operating lugs simultaneously with the unlocking of the breech bolt which engaging movement is effected by the reaction of the main spring against the breech bolt and the slide thereby causing said breech bolt and slide to meet and permitting them to reciprocate together.

23. In a rifle action, a receiver having locking lug races, a breech bolt having locking lugs and a safety lug and helical grooves, and an operating slide provided with operating lugs engaging in said grooves for

turning the breech bolt into locked and unlocked positions and move said bolt along said receiver races when reciprocated, said helical grooves having means on both sides of each to serve as stops with respect to said operating lugs, said stops being so located that the longitudinal movement of the operating slide necessary to lock said bolt is shorter than the longitudinal movement of the slide necessary to unlock the bolt. 55

24. In a rifle action, the combination of a receiver having locking-lug-recesses, lug-races and an inclined surface, a breech bolt having locking lugs, a safety lug, an extracting cam, and helical grooves, an operating slide having lugs adapted to engage said helical grooves to lock, and unlock said breech bolt and to move same along the receiver races when the slide is reciprocated; a firing pin assembly, a bolt sleeve adapted to be screwed into said breech bolt, a cocking piece associated with said sleeve and bolt, means whereby the operating slide will cause the breech bolt to rotate through a certain angular distance before said extracting mechanism beings to act. 60

25. In a rifle action, the combination with a receiver, of an operating slide and a breech bolt assembly comprising a breech bolt arranged for longitudinal movement 80 with respect to said slide when said bolt is unlocked, a firing pin, a main spring surrounding said pin, a cocking piece, a bolt sleeve adapted to be screwed into the breech bolt, and means whereby said longitudinal 85 movement is automatically taken up by the main spring in sequence with the unlocking movement.

26. In a rifle action of the rectilinear type, comprising a bolt, a bolt-sleeve containing 90 means to hold the firing pin assembly in its rearmost position with respect to said bolt sleeve, and an operating slide, and means whereby said action is adapted to be locked and unlocked, open and closed, when the 95 firing pin is at safety position.

Signed at Seattle, Washington, this 24th day of September, 1923.

CHARLES D. MEYER.
